A. LANKA

ACCORDION

Filed May 12, 1927

Fig. 1

Fig. 2

Inventor:
Artur LANKA
by George C. Heinrich
Attorney.

UNITED STATES PATENT OFFICE.

ARTUR LANKA, OF GERA, GERMANY.

ACCORDION.

Application filed May 12, 1927. Serial No. 190,821.

This invention relates to improvements in accordions or similar musical instruments, and more particularly in the means for seating and closing the air-valves of such instruments, and it is the principal object of my invention to provide a novel and improved mechanism for closing the valves tightly, while a spring, tensioned during the opening of the valves by the proper operation of the keys of the instrument, returns the parts into their normal positions.

Another object of the invention is the provision of a valve operating mechanism for musical instruments, preferably accordions, equipped with means for allowing the simultaneous opening of the valves for the bases and seconds, while permitting a separate operation of these mechanisms by their individual links.

20 A further object of my invention is the provision of a novel and improved valve closing mechanism for accordions and the like musical instruments replacing the customary spring closure by a system of levers 25 and plates under the action of an adjustable bolt for effecting a positive and airtight closure of the valves.

In the accompanying drawing, forming a material part of this disclosure:

30 Fig. 1 is a sectional fragmentary elevation of an accordion equipped with a novel valve seating mechanism constructed according to my invention.

Fig. 2 is a detail view of the valve seating mechanism per se on an enlarged scale.

35 As illustrated on the drawing, a link *a* is pivotally secured at one end to the angle-iron or plate *b* to which is also attached one end of a valve-lifter *c* fulcrumed intermediate its ends to the head part of a guide member *e* for the valve-plate *d* secured at one of its ends in any suitable manner to said valve plate "*d*" and pivoted at its other end to a lug in the instrument, while the extreme outer end of lifter *c* is attached to said guide member of the valve-plate *d* for lifting the same.

The plate *b* is also engaged by a threaded bolt *f* adjustable in a vertical direction by means of the counter nuts *g* on the threaded parts of the bolt, one on each side of an arm of a bracket *h* through which the bolt passes, attached to the frame of the accordion or the like, and adapted to firmly engage the same 55 for locking the bolt in its adjusted position.

A spring *i* is connected at one end to the

upper end of bolt *f* and at its opposite end to an arm of the angle plate *b*; said spring is tensioned during the lifting of the valve-plate, and returns the same onto its seat, 60 in which position the valve lifter *c*, the plate *b*, and the bolt *f* are in their stretched dead-center position, in which the valve-plate is firmly held on its seat in order to effect a perfect airtight closure, in which the lower 65 part *c'* of the valve-lifter *c* is firmly engaging the bass valve-plate *d*, and a displacement of the parts toward the rear is positively prevented.

It will be evident, that the pressure exerted on valve-plate *d* may suitably be regulated by the proper adjustment of bolt *f*.

Simultaneously with the operation of the bass-plate *d* the operating mechanism for the second-plate *l*, which is similarly constructed 75 as above described with respect to bass-valve plate *d* is operated by a member *k* normally engaging the plate *d* and lifted with the same for actuating the operating mechanism for the second plate *l* which however can also 80 be operated independently by means of its link *a*.

The operation of my novel valve-mechanism will be entirely clear from the above detailed description thereof, and it will be 85 clear that a positive, firm and airtight closure of the valves is achieved by the increase in pressure on the valve-plate, while the pressure on the keys is made independent of the size of the plate, and the operation of 90 the keys is thereby greatly facilitated.

It is to be understood that while I have described and shown the preferred form of constructing my device in practice, such changes as come within the scope of the 95 appended claims may be made in the construction of the minor details thereof without departing from the gist of my invention as disclosed.

Having thus described my invention, what 100 I claim as new and desire to secure by Letters Patent is:

1. Valve operating mechanism for key-operated, valved musical instruments including their valve-plates comprising operating keys, a system of levers and plates, adjusting means for the valve plate, a spring connected to said system of levers and plates and adapted to be tensioned during the lifting of the valve-plate by the operation of 105 said keys, and to close the same by its expansion positively and airtight upon the re-

lease of said keys, said lever and plate system assuming a stretched dead center position preventing an upward movement of the valve-plate and a bending of the said lever and plate system.

2. Valve operating mechanism for key-operated accordions and the like musical instruments including their valve plates, and guides therefor comprising a key-operated link, and angular plate to which said link is secured, a curved lever attached to said plate and to the guide of the valve-plate, and a valve lifter formed with said lever firmly engaging said valve-plate for holding the same airtight against its seat.

3. Valve operating mechanism for key-operated accordions and the like musical instruments comprising an angular plate, a threaded bolt vertically engaging said plate at its upper end, a spring secured at one end to an extension of said angular plate and at

its other end to said bolt at the upper end thereof, and adjusting counter nuts on said bolt for permitting an adjustment of the pressure on the valve-plate on its seat in its position of rest, and an angular lever secured to said angular plate and said valve-plate.

4. Valve operating mechanism for key-operated accordions and similar musical instruments including bass and second valves, valve-plates for said valves, and systems of levers and plates for operating the same upon the operation and release of said keys, a member engaging the bass valve-plate and operatively connected to the second valve-plate for operating both the bass and the second valve simultaneously.

Signed at Gera, in the county of Thüringen and State of Germany this 22d day of December, A. D. 1927.

ARTUR LANKA.
